SPINDLE OILING DEVICE

Karl W. Meklenburg, Whitinsville, Mass., assignor to Whitin Machine Works, Whitinsville, Mass., a corporation of Massachusetts

Application December 5, 1936, Serial No. 114,455

5 Claims. (Cl. 308—169)

This invention relates to spinning and twisting spindles and more particularly to oiling devices therefor.

It has been found in the operation of such spindles that a crooked or unbalanced spindle will sometimes pump oil out of a spindle base and cause a spindle to run dry in a comparatively short time after oiling. It has also been found that lint or dirt accumulated around the upper part of the spindle base will sometimes cause oil to be siphoned out over the top of the base.

It is the general object of my invention to provide an improved spindle oiling device so designed that pumping or siphoning of oil from the spindle base will be effectively prevented.

More specifically, I provide means for air-tight sealing of the oil supply passage, so that escape of oil will be prevented by external atmospheric pressure.

My invention further relates to arrangements and combinations of parts which will be herein-after described and more particularly pointed out in the appended claims.

25 A preferred form of the invention is shown in the drawing, in which

Fig. 1 is a sectional side elevation of a spindle embodying my improvements;

Fig. 2 is a plan view thereof;

30 Fig. 3 is a view similar to Fig. 2 but showing the parts in a different position;

Fig. 4 is a side elevation of a combined doffer guard and oil cover; and

Fig. 5 is a side elevation, partly in section, of 35 a valve member with the doffer guard pivoted thereto.

Referring to the drawing, I have shown a portion of a spindle rail 10 having a spindle base 11 mounted therein and secured by the usual 40 clamping nut 12. A spindle blade 14 is provided with a whirl 15 and is rotatably mounted in a bushing or bolster 16, inserted in a cylindrical bearing 17 in the upper part of the base 11. The lower part of the base is provided with an enlarged oil chamber 18.

The parts thus far described are all of the usual construction.

The device for supplying oil to the chamber 18 comprises a laterally projecting portion 20 having an oil passage 21 therein, and an upright member 22 having a cylindrical passage 23 intersecting the passage 21, and having also an inclined branch passage 24 intersecting the passage 23. A valve member 30 is mounted in the cylindrical passage 23 and is provided with a central

recess 31 (Fig. 5) in its lower end portion and with a side port 32 communicating therewith.

A combined doffer guard and oil cover 35 is pivotally connected to the upper end of the valve member 30 by a cross pin 36. One end portion 38 of the part 35 normally extends over the edge of the whirl 15 and forms a guard which prevents upward displacement of the spindle during the doffing operation. The other end portion 41 of the part 35 is inclined outwardly and downwardly and forms a cover for the upper end of the inclined passage 24. The portion 41 excludes dirt but is not depended on for sealing action. Side flanges 42 (Fig. 5) are also provided, which flanges embrace the sides of the upright member 22 of the oiling device when the parts are in the position shown in Figs. 1 and 2 and prevent accidental angular displacement thereof. The part 35 may desirably be formed of sheet metal.

A stop 44 is provided on the upper end of the upright member 22, which stop limits angular movement of the part 35 and valve member 30 to 90°.

In order to prevent upward displacement of the valve member 30, an annular groove 46 (Figs. 25 1 and 5) is provided in the upper part of the member 30, and a cross pin 48 is inserted through the upright member 22 to hold the valve member 30 to 35 the axial displacement.

When the parts are in the position shown in 30 Figs. 1 and 2, the port 32 in the valve member 30 is at 90° from the passage 24 and the oiling device is thus effectively sealed. When the part 35 and valve member 30 are turned to the position shown in Fig. 3, the oil passage 24 is uncovered and the port 32 is aligned with the passage 24, so that oil may be supplied to the spindle base through the passage 24, port 32, recess 31 and passage 21. Also when the parts are in the position shown in Fig. 3, the doffer guard is 40 inoperative and the spindle may be removed if desired.

Having thus described the details of construction of my improved spindle oiling device, the use and advantages thereof will be readily apparent. The outstanding feature is the effective sealing of the oil passages by the valve member 30, so that no air can enter the passage 21 or the oil chamber 18. Consequently no oil can be pumped or siphoned out of the upper end of the 50 cylindrical bearing 17, as such removal of oil would produce a partial vacuum in the chamber 18 and the escape of oil would be prevented by the atmospheric pressure at the top of the bearing 17.

I thus secure all of the advantages of a certain old type of spindle having no provision for oiling except by removal of the spindle and supplying oil directly through the spindle opening, 5 while at the same time I retain the advantages of the more modern type of spindle having provision by which the spindles may be oiled while the machine is running and without removal of the spindles.

10 In addition, I secure the advantage of sealing the oil supply passage air-tight, so that pumping or siphoning of oil is made impossible.

Having thus described my invention and the advantages thereof, I do not wish to be limited 15 to the details herein disclosed, otherwise than as set forth in the claims, but what I claim is:—

- 20 1. In a spindle, a spindle base having an oil supply device at one side with an oil passage therethrough, a valve member intersecting said passage and effective to open and close said passage at a point between the ends of said passage and substantially removed from the outer end thereof, and a doffer guard mounted on said valve member and by which said member may be turned, said guard being also effective to cover the outer end of said passage when said passage is closed by said valve member.
- 25 2. In a spindle, a spindle base having an oil supply device at one side with an oil passage therethrough, a valve member intersecting said passage and effective to open and close said passage at a point between the ends of said passage and substantially removed from the outer end thereof, and a combined doffer guard and oil cover pivotally mounted on said valve member and by which said member may be turned, the outer end of said passage being covered by said guard when the passage is closed by said valve and said guard having a free swinging movement relative to said valve member.

40

3. In a spindle, a spindle base having an oil supply device at one side with an oil passage therethrough, a rotatable valve member to open and close said passage, a combined doffer guard and oil cover pivotally mounted on said valve member to swing about an axis perpendicular to the axis of said valve member and by which said member may be turned, and means to retain said valve member and said combined guard and cover in operative position in said spindle base.

4. In a spindle, a spindle base having an oil supply device at one side with an oil passage therethrough, means to cover said passage at its outer supply end, means to close said passage at a point between its ends and substantially removed from both ends of said passage against flow of oil or air through said passage, and manual means to actuate said first means to uncover the outer end of said passage and to simultaneously actuate said second means to open said passage at said intermediate point, said first and second means being mechanically and operatively connected to each other.

5. In a spindle, a spindle base having an oil supply device at one side with an oil passage in the lower part of said device, a second oil passage intersecting said first oil passage, a cylindrical valve member mounted in said second passage and having a central recess, an oil inlet passage intersecting said second passage, a port 30 in said valve member communicating with said recess and alignable with said oil inlet passage, a combined doffer guard and oil cover pivoted to the upper end of said valve member and effective for turning said member to move said port 35 into and out of alignment with said inlet, and means to limit turning movement of said valve member in both directions.

KARL W. MEKLENBURG. 40
